POSITIVE PEDESTAL SWITCHED VIDEO TUBE

Filed Sept. 7, 1949

UNITED STATES PATENT OFFICE

2,584,144

POSITIVE PEDESTAL SWITCHED VIDEO TUBE

Peter T. Maresca, Asbury Park, N. J., assignor to the United States of America as represented by the Secretary of the Army

Application September 7, 1949, Serial No. 114,443

5. Claims. (Cl. 315—26).

(Granted under the act of March 3, 1883, as amended April 30, 1928; 370 O. G. 757)

1

The invention described herein may be manufactured and used by or for the Government for governmental purposes, without the payment of any royalty thereon.

My invention relates to improvements in electronic switching circuits, and more particularly to such a circuit as embodied in a keyed amplifier.

In certain radar systems, it is sometimes necessary to switch electronically a video stage handling positive video signals. One of the required characteristics of such a system or circuit, is that the video signal be of the same polarity as the accompanying pedestal. In some radar applications, it is important to intercept two video signals for simultaneous observation and comparison of the same, on the screen of a cathode-ray tube. The respective pedestals accompanying the two video signals can be eliminated or blanked out, but for the purposes of observation and comparison at the point of reception, they are needed to effect displacement on the screen of the two images.

Ordinarily, when a tube is switched on, a negative pedestal is produced in the plate circuit thereof. Therefore, where a positive video signal is being handled and no inversion is desired, it becomes necessary to employ an extra, inverting tube.

With the foregoing in mind, it is one of the objects of my invention to provide an improved electronic switching circuit of the character referred to, wherein the desired conditions of video switching are satisfied, without use of an extra, inverting stage.

Another object of my invention is to provide an improved system or circuit of the character referred to, wherein there is a display of two video signals going, respectively, in opposite directions, displaced one below the other, with time sharing on a common cathode-ray tube, and with the intrinsic characteristic that each image is free to act independently of, or without influence from the other.

Another object of my invention is the provision of an improved circuit of the character referred to, which has advantages over those proposed heretofore in the way of being consistently reliable, and positive in performance.

Other objects and advantages will hereinafter appear.

For the purpose of illustrating my invention, an embodiment thereof is shown in the drawing, wherein

Fig. 1 is a simplified, diagrammatic view of an

electronic switching circuit constructed and operating in accordance with my invention; and Fig. 2 is a graphical illustration of the operating action in Fig. 1.

With reference to the drawing, the numerals 19 and 21 designate, respectively, two screen-grid switching tubes. Two sources of video signals, shown for simplification as the two input lines or connections 14 and 16, impress the intercepted video signals 10 and 11, through the respective condensers 17 and 18, on the cathodes 19a and 21a of the switching tubes.

The tubes 19b and 21b are associated, respectively, with switching tubes 19 and 21, and function to produce or form pedestals of the same, positive polarity as the video signals 10 and 11.

Timing of the switching action is effected by the two rectangular voltage waves 27 and 28 which are supplied from the two sources or wave generators 27a and 28a, respectively. These voltage waves are impressed on the grids of tubes 19c, 19d, 21c and 21d, as shown. The two generators 27a and 28a may be of a conventional design, and the respective output voltage waves 27 and 28 therefrom are 180 degrees out of phase, as represented in Fig. 1.

In the operation of my improved circuit, the video signal 10 is applied to the cathode 19a of switching tube 19, is amplified by the latter, and appears as signal output in the plate circuit thereof. Pedestals of positive and the same polarity as the video signal 10, appear in the plate circuit of the pedestal-forming tube 19b during the active, conducting period of tube 19. The output video signal from tube 19 combines with the positive pedestal from tube 19b, and the two, appearing in the common plate or output connection, are applied as shown to the upper vertical deflecting plate 12 of a cathode-ray tube 13. Accordingly, the visual indication 10a, which is that of the video signal 10, appears on the fluorescent screen of the cathode-ray tube. When the voltage of rectangular wave 27 from the tube 19c is positive on the screen grid 19g of switching tube 19, the latter conducts, and the amplified video signal 10 appears in its output plate circuit. During the intervening periods, when the voltage of wave 27 from tube 19c drops to practically zero, tube 19 is keyed, or made non-conductive.

In like manner, the voltage wave 28 applied from tube 19d to the grid of the pedestal-forming tube 19b, keys the latter. Since the wave 28 is 180 degrees out of phase with the wave 27, it will be seen that the pedestals from tube 19b

appear on the vertical deflecting plate 12 at spaced periods which intervene the spaced periods during which the video signal 10 from tube 19 appears on plate 12.

The cooperative action and resultant effect of tubes 21, 21b, 21c and 21d is the same as above. That is, the video signal 11 is applied to the cathode 21a of switching tube 21, is amplified by the latter, and appears as signal output in the plate circuit thereof. Pedestals of positive sign and the same polarity as the video signal 11, appear in the plate circuit of the pedestal-forming tube 21b during the active, conducting period of tube 21. The output video signal from tube 21 combines with the positive pedestal from tube 21b, and the two, appearing in the common plate or output connection, are applied as shown to the lower vertical deflecting plate 12a of cathode-ray tube 13. Accordingly, the visual indication 11a, which is that of the video signal 11, appears on the fluorescent screen of the cathode-ray tube. When the voltage of rectangular wave 28 from the tube 21c is positive on the screen grid 21g of switching tube 21, the latter conducts, and the amplified video signal 11 appears in its output plate circuit. During the intervening periods, when the voltage of wave 28 from tube 21c is practically zero, tube 21 is keyed, or made non-conductive.

In like manner, the voltage 27 applied from tube 21d to the grid of the pedestal-forming tube 21b, keys the latter. As above, since the wave 27 is 180 degrees out of phase with the wave 28, the pedestals from tube 21b appear on the vertical deflecting plate 12a at spaced periods which intervene the spaced periods during which the video signal 11 from tube 21 appears on plate 12a.

Fig. 2 shows the potential at vertical deflecting plate 12 relative to ground potential. Time t_1 represents the negative half cycle of switching wave 27 and the positive half cycle of switching wave 28. It will be seen that during the time t_1 tube 19b is conducting and tube 19, which then has a negative potential on the screen grid 19g, is cut off. Resistor 19f is adjusted so that tube 19b draws 10 milliamperes. This 10 millampere current causes a 200 voltage drop across resistor 19e, which has 300 volts applied thereto. This leaves vertical deflecting plate 12 at a potential of 100 volts, as shown in Fig. 2. At the end of time t_1 , switching waves 27 and 28 change in polarity, whereby for an instant both tubes 19 and 19b are cut off and the entire 300 volts are applied to vertical deflecting plate 12. Then, for the rest of time t_2 , tube 19b is cut off and tube 19, which now has a positive voltage on screen grid 19g, becomes conducting. The 10,000 ohm resistor in the cathode circuit of tube 19 is adjusted so that tube 19 draws a quiescent current of 5 milliamperes. The 5 millampere current causes a 100 voltage drop across resistor 19e so that the quiescent voltage on vertical deflecting plate 12 is now 200 volts. Video signal 10 and noise applied as an input to tube 19 causes the 200 volt quiescent potential at vertical deflecting plate 12 to vary in the manner shown in Fig. 2.

Since tubes 21 and 21b are rendered conducting 180° out of phase with tubes 19 and 19b, respectively, the potential on vertical deflecting plate 12a will vary in a manner similar to the potential on deflection plate 12, shown in Fig. 2, except that vertical deflecting plate 12a will have a quiescent potential of 200 volts during time t_1 and a potential of 100 volts during time t_2 . It will be seen, therefore, that the vertical trace

produced on the face of the cathode ray tube, which is determined by the potential differences existing between vertical deflecting plates 12 and 12a, will be as shown in Fig. 1.

From the foregoing, it will be understood that the switching tubes 19 and 21 constitute the respective, keyed video stages. Tube 19 receives on its cathode 19a the positive video signal 10, and delivers positive video signal riding on positive pedestals from tube 19b. In like manner, tube 21 receives on its cathode 21a the positive video signal 11, and delivers positive video signal riding on positive pedestals from tube 21b.

The cathode-ray tube 13 is provided with the usual horizontal-deflecting plates (not shown). To these may be applied a saw-tooth voltage wave having a sweep-frequency, for example, of 500 cycles.

Pedestal height is controlled by adjustment of the variable resistors 19f and 21f. In each of the two channels, there is but the one tube 19b and 21b, respectively, for controlling pedestal height. Signal inversion is avoided by driving the respective cathodes 19a and 21a of tubes 19 and 21, instead of their respective grids 19g and 21g.

Other advantages of my improved circuit reside in the fact that there is continuous control of the separation x between the two phenomena appearing on the screen of tube 13, and the fact that no fixed cut-off bias on either of the switched amplifier stages 19 and 21 is required. There is also, elimination of the pulse transformers. Unless they are of a special design, these transformers are unable to pass a long switching wave which is necessary for efficient operation. Otherwise, the operating action of the circuit is limited to very short switching intervals. In my improved circuit, a saving of tubes is effected by employing tubes as amplifiers, thereby providing voltage gain in addition to the other functions. Also, by adjusting either or both of the potentiometers 19f and 21f, there is the possibility of continuous adjustment of pedestal height to change the image separation, represented at x in Fig. 1.

The various circuits proposed heretofore and which have a cathode output, rely upon signal not being present in the cathode circuit in the absence of plate voltage. However, on account of diode action, it is possible to pass signal in the absence of plate voltage, should the input voltage approach the bias. In my improved circuit, on the other hand, screen-grid switching is employed, which definitely controls signal passage through the tube.

In the prior art complete elimination of pedestal is the object, whereas in my improved circuit, there is the provision for choice of pedestal or transient, or complete elimination thereof by adjustment of the tubes 19 and 21. Another important feature in my improved circuit resides in the elimination of leakthrough of undesired signals.

The broader aspect of my invention resides in the improved method whereby a positive pedestal may be produced in the plate circuit of an electronically switched video tube.

Some of the practical applications of my improved method and circuit would be in radar display circuits where time sharing techniques are used, in experimental electronic switching circuits, for dual display purposes for testing IFF systems, and generally, in systems requiring dual sweep displays.

The respective values of resistors, condensers and voltage given in Fig. 1, are not critical, and

may vary over a substantial range to suit particular requirements. The tubes which might be used in my improved circuit are identified in Fig. 1 by their respective type numbers and letters, as used in the trade.

The embodiment of my invention disclosed in Fig. 1 is considered to be a preferred form thereof, but it will be obvious to those skilled in the art that various modifications are possible without departing from the spirit of my invention, or the scope of the claims.

I claim as my invention:

1. An electronic switching circuit comprising a first signal amplifier including first and second electron tubes and a first common impedance in the output circuit of said first and second electron tubes, a second signal amplifier including third and fourth electron tubes and a second common impedance in the output circuit of said third and fourth electron tubes, means for applying a first signal to the input circuit of said first tube, means for applying a second signal to the input circuit of said third tube, a source of square-wave voltage, means for rendering said first and fourth tubes conducting only during alternate half-periods of said square-wave voltage, means for rendering said second and third tubes conducting only during half-periods of said square-wave voltage intermediate said alternate half-periods, and means for applying the potential difference between the voltage appearing across said first common impedance and the voltage appearing across said second common impedance as an input to a utilization means.

2. In combination with a cathode ray oscilloscope having an electron beam and a screen, wherein the electron beam thereof is periodically deflected along a first coordinate; an electronic switching circuit for providing a dual display of first and second signals on said screen, said switching circuit comprising a first amplifier including first and second electron tubes and a first common impedance in the output circuit of said first and second electron tubes, a second amplifier including third and fourth electron tubes and a second common impedance in the output circuit of said third and fourth electron tubes, means for applying said first signal to the input circuit of said first tube, means for applying said second signal to the input circuit of said third tube, a source of square-wave voltage, means for rendering said first and fourth tubes conducting only during alternate half-periods of said square wave voltage, means for rendering said second and third tubes conducting only during half-periods

intermediate said alternate half-periods, and means for applying the potential difference between the voltage appearing across said first common impedance and the voltage appearing across said second common impedance to said cathode ray oscilloscope to effect the deflection of said electron beam along a second coordinate perpendicular to said first coordinate in response to said potential difference.

10 3. The combination according to claim 2, wherein said first amplifier includes means for varying the gain of said first tube relative to the gain of said second tube, and said second amplifier includes means for varying the gain of said third tube relative to the gain of said fourth tube.

15 4. The combination according to claim 2, wherein said first and third electron tubes include a screen electrode, and wherein said means for rendering said first and fourth tubes conductive include means for applying a positive potential to the screen electrode of said first tube relative to the cathode thereof only during said alternate half-periods of said square-wave voltage, and said means for rendering said second and third tubes conductive include means for applying a positive potential to the screen electrode of said third tube relative to the cathode thereof only during said intermediate half-periods of said square-wave voltage.

20 5. The combination according to claim 2, wherein said first and second signals are injected at the cathodes of said first and third tubes, respectively.

PETER T. MARESCA.
